[57] **CLAIM**

The ornamental design for a fender for cart, as shown and described.

DESCRIPTION

FIG. 1 is a top right front perspective view of a fender for cart showing our new design, in reduced scale; the broken line showing of a cart is for illustrative purposes only and form no part of the claimed design;
 FIG. 2 is a right side elevational view thereof;
 FIG. 3 is a top plan view thereof;
 FIG. 4 is a bottom plan view thereof;
 FIG. 5 is a left side elevational view thereof;
 FIG. 6 is a front elevational view thereof; and,
 FIG. 7 is a rear elevational view thereof.
